UNITED STATES PATENT OFFICE.

DAVID J. BILLER, OF ST. LOUIS, MISSOURI, ASSIGNOR TO DAY-BRITE REFLECTOR COMPANY, OF ST. LOUIS, MISSOURI.

DESIGN FOR A REFLECTOR HOUSING FOR DISPLAY-CASE LIGHTS.

Application filed October 31, 1927. Serial No. 23,953. Term of patent 14 years.

To all whom it may concern:

Be it known that I, DAVID J. BILLER, a citizen of the United States, and a resident of the city of St. Louis, State of Missouri, have invented a new, original, and ornamental Design for a Reflector Housing for Display-Case Lights, of which the following is a specification.

In the accompanying drawing, which forms part of this specification,

Fig. 1 is a front elevation of a reflector housing for display case lights embodying

my invention, the dotted lines indicating the upper portion of a display case,

Fig. 2 is an end elevation thereof,

Fig. 3 is a cross sectional view thereof,

Fig. 4 is a view looking at the housing from the bottom; and

Fig. 5 is a top plan view.

I claim:

The ornamental design for a reflector housing for display case lights, as shown.

DAVID J. BILLER.
